UNITED STATES PATENT OFFICE

124,974

DESIGN FOR AN OVERSHOE OR THE LIKE

Leslie H. L'Hollier, Waltham, Mass., assignor to
The B. F. Goodrich Company, New York, N. Y., a corporation of New York

Application May 24, 1940, Serial No. 92,559

Term of patent 14 years

To all whom it may concern:

Be it known that I, Leslie H. L'Hollier, a citizen of the United States, residing at Waltham, in the county of Middlesex and Commonwealth of Massachusetts, have invented a new, original, and ornamental Design for an Overshoe or the Like, of which the following is a specification, reference being had to the accompanying drawing, forming a part thereof, of which the figure is a front perspective view of an overshoe showing my new design, the opposite side presenting substantially the same appearance as the side shown.

I claim:

The ornamental design for an overshoe or the like, as shown and described.

LESLIE H. L'HOLLIER.
